UNITED STATES PATENT OFFICE.

JOSEPH D. HOBBS, OF MOUNT PLEASANT, IOWA.

DITCHING-PLOW.

SPECIFICATION forming part of Letters Patent No. 278,549, dated May 29, 1883.

Application filed December 27, 1882. (No model.)

To all whom it may concern:

Be it known that I, JOSEPH D. HOBBS, of Mount Pleasant, in the State of Iowa, have invented a new and useful Improvement in Ditching-Plows; and I do hereby declare that the following is a full, clear, and exact description of the same.

My invention is a ditching-plow adapted to move in the ditch which it forms, so as to be guided by the ditch itself to cut at any desired inclination and automatically indicate the inclination.

The invention consists of special improvements in several particulars, all hereinafter fully described and particularly explained.

In the accompanying drawings, Figure 1 shows a side elevation of the apparatus, partly in section, as hereinafter explained. Fig. 2 represents a rear elevation of the apparatus located within the ditch.

I proceed first to describe the construction of the main supporting and driving wheel of the ditcher. It consists of a hub, B, having a tier of spokes near each end. These spokes are strengthened by a drum, C, and have felloes H H, provided with holes through the rim or tire, for the purpose described hereinafter. The drum C extends from one set of spokes to the other and is firmly secured to both sets, thus firmly uniting and strengthening the two wheels and making them, in effect, one solid wheel. The hub is mounted upon a bolt set in the rear ends of the side bars, X X, and turns freely between them. Upon these rear ends are set vertical standards A A, in the upper ends of which is a drum, J, over which one end of a belt, F, passes, and upon the shaft of which, outside of the drum, are fixed pinions I I, gearing into the holes in the face of the large wheel. The lower end of the belt is carried by a small pulley, K, mounted upon a shaft, 2, extended through the heels L L of the plow sides O O. These heels L L may be provided with suitable caster-wheels to allow the machine to run easier and with less friction. The belt F, which may be of any ordinary construction, passes through between the braces R' R', which, with the belt, form a long open box, which serves to keep the carrying-pulleys J K their proper distance from each other, the box preventing the dirt from falling off the belt until it is car-

ried over the upper pulley, J. When so carried over it is received by an inclined chute, S, which extends to one side, as shown in Fig. 2, and delivers the dirt at a suitable distance 55 from the side of the ditch. The chute S is connected to the upright standards A A and to the upper end of the box R', as shown in Fig. 1.

Connected to the rear end of the chute S is a handle, T, by means of which the operator 60 can guide the machine until it has cut deep enough into the earth to find support therein. The rest of the frame-work of the machine is shown clearly in the side elevation.

The side bars, X X, extend over the hub to 65 the front of the machine, and are bolted to the sides of the box R, whereby the whole structure is firmly braced. Between them, at the frontend, passes a connecting-bar, W, by means of which suitable elevation may be given to the 70 cutting-edge N of the plow M by moving it vertically upon the pivoting-bolt 2. The rear edge of the bar is toothed and meshes into a worm upon the hand-shaft Z, by means of which it may be adjusted vertically or held in any desired 75 position. Pivoted between the side bars is a cam, 5, the shaft of which is provided with a handle, 4, the cam, when properly turned, bearing upon the front edge of the bar W and holding it in contact with the worm; but upon turning the handle the bar may be quickly released and as quickly adjusted vertically without turning the shaft Z. The front edge of the bar W is made with a series of holes for a vertically-adjustable clevis, 6.

The sides O O of the plow M are set at a proper width to cut the ditch, and are provided with sharp edges on the front. To the rear part of one of these sides is attached a vertical bar, U, which carries upon its upper end an adjustable level, V, adapted to show the inclination at which the plow is cutting. The plow being set for any required angle of inclination, the level V must be reversed upon return, which is done by changing its position upon the supporting-bracket 8, on which it is held by a spring, 9, as shown in Fig. 1. The bar U is held in any proper position by the arc 7. The bar U also serves as a lever for raising the plow at the end of the ditch, and by means of the rack in the arc 7 and a suitable connecting-catch the bar U serves to hold the plow up

when turning around at the end. The bar W is connected firmly to the worm by the cam 5, and the whole frame-work is rigidly secured together and well braced at different parts, and 5 the plow being set at the proper angle, it acts upon the principle of a plane. The bottom of the plow M is curved up, as shown at P, to guide the earth up to and upon the belt. By this construction the apparatus can be made 10 to cut a straight and even bottom at any desired inclination.

It will be obvious that the apparatus is especially adapted for tile-ditching; but I do not limit the use of my invention to this particular 15 adaptation.

Instead of the chute S, a cross-belt may be provided, running at right angles to the belt F, and driven by ordinary beveled gears from the same shaft to which the pinions I are connected, and in such relation to the main carrier as to receive the dirt which is deposited from 20 the buckets thereof and carry it a suitable distance away from the ditch, where it is deposited.

25 What I claim is—

1. In a ditching-machine, the wheel consisting of the hub having spokes near its ends, the drum C, and the fellies H H, said wheel being adapted to move in the ditch, all sub- 30 stantially as described.

2. The combination, with the described wheel, side bars, X X, and vertical standards A A, of the box R and belt and mechanism for driving the same, all as set forth.

35 3. In combination with the wheel, constructed as described, the drum J, the pinions I I, fixed upon the shaft, and the standards A A, operating in connection with the belt and open box R, substantially as described.

40 4. The combination, with the wheel having perforated rim, of the pinion meshing therein

and giving motion to the elevating-belt, and a chute, S, bolted to the standard, substantially as described.

5. The combination, in a ditcher, of the side 45 bars, X X, pivoted plow M, belt F, and the cogged bar W, worm-shaft Z, and cam 5, substantially as described.

6. In combination with the vertically-adjusting bar W, pivoted plow, and side bars, X 50 X, the clevis 6, adapted to the adjusting-holes of the bar, substantially as described.

7. The combination of the vertically-adjustable plow and the operating-lever U with the level V, carried upon such bar, substantially as 55 described.

8. The combination of the plow M, vertically adjustable, as described, and the bar U, fixed to said plow, and the level V, substantially as 60 described.

9. The combination of the pivoted plow M, vertically-adjustable bar W, having teeth engaging with worm upon the shaft Z, and the cam 5 and bar U, operating as a hand-lever, substantially as described.

65 10. The combination of the plow M, the box R', and feeding-belt of a ditcher, and the bar U, arc 7, provided with teeth and acting in connection with the bar U, and the level, as described.

11. In combination with the plow of a ditcher, the bar U and the reversible level V, resting upon suitable support, with suitable holding-spring, as described.

In testimony whereof I have signed my name 70 to this specification in the presence of two subscribing witnesses.

JOSEPH D. HOBBS.
